UNITED STATES PATENT OFFICE.

JOHN HARRIS, OF SHEFFIELD, ENGLAND.

ORE-ROASTING FURNACE.

1,203,613.

Specification of Letters Patent. Patented Nov. 7, 1916.

Application filed July 30, 1914. Serial No. 854,143.

To all whom it may concern:

Be it known that I, JOHN HARRIS, a subject of the King of England, residing at Sheffield, Yorkshire, in England, have invented certain new and useful Improvements in Ore-Roasting Furnaces, of which the following is a specification.

This invention relates to rabbling appliances for mechanical ore roasting furnaces of the type in which the rabble arms project into the interior of a hollow shaft longitudinally divided into channels for the conveyance of the cooling fluid to the arms its object being to provide improvements in the means 10 for securing the arms to the shaft and in the arrangement of pipes for supplying cooling water to the arms by the employment of which, when the arms are water cooled the shaft itself may be air cooled with or without 15 a forced draft and any one arm may be more easily and quickly removed or replaced without disturbing any other parts, while the same fittings may be used to secure, when desired, an air cooled arm to the shaft.

20 In the accompanying drawings:—Figure 1 is a broken vertical section of the upper part of a rabble shaft according to this invention. Fig. 2 is a section on the line 2—2 of Fig. 1. Fig. 3 is a section on the line 30 3—3 of Fig. 1. Fig. 4 is a vertical section of an air cooled arm. Fig. 5 is a vertical section of the upper part of the shaft illustrating a modification.

Like letters indicate like parts throughout 35 the drawings.

The hollow shaft A is longitudinally divided into channels corresponding in number to that of the arms, the shaft illustrated being intended to carry four arms, each 40 operating at a different level. An outwardly projecting hollow lug B is formed on the shaft for each arm, and the hollow of each lug communicates with a different one of the longitudinal channels formed in the shaft. Only one lug is illustrated the others 45 being of similar construction.

A transverse hole C is made through the lug B and intersects one side of the hollow therein, which is preferably but not necessarily of rectangular cross-section, as shown in Figs. 1 and 2. The rabble arm D is provided with a base portion D¹ which approximately fits the hollow of the lug B. One end of the base D¹ extends into the hollow shaft 50 and the other end is formed with a flange D² adapted to engage the outward end of the

lug B. A groove D³ is formed across the base D¹ and is so situated that when the arm is in position it registers with the hole C in the lug. The lower face of the groove 60 D³ is slightly tapered as shown in Fig. 2 and after the base of the arm has been inserted into the lug a cotter E of like taper is driven into the hole C and, engaging the groove D³, locks the arm in place. Preferably 65 the cotter is of less length than the distance across the lug B so that it is wholly contained therein, both ends of the hole C being afterward plugged by a suitable refractory filling. Although it is preferred 70 that both the cotter E and the groove D³ be tapered, one or both of them may have parallel sides if desired.

The lower face of the interior of the hollow lug B conveniently slopes slightly 75 upward from the interior of the shaft to the end of the lug, and the base D¹ of the arm D may be provided with a corresponding taper, in order to add to the rigidity of the fastening when the cotter E is driven into 80 place.

The water cooled arm shown in Figs. 1, 2 and 3 is formed with two cylindrical passages or holes D⁴ which extend through the arm and are closed by any known means 85 such as removable plugs, caps or the like F, the usual feed and discharge water pipes being screwed into two separate short holes each communicating with one of the passages D⁴ as indicated in Figs. 1 and 3. At 90 the outer end of the arm the passages D⁴ communicate with each other as usual to enable the water to circulate and are closed by removable caps D⁵ or the like. The detachability of the arm from the shaft acts 95 to prolong the life of the arm in cases where the passages D⁴ therein are liable to become choked by deposits of "fur" from the water; for as soon as any overheating of the arm or decreased circulation of water therein is observed, the arm may be dismounted and, after the caps F and D⁵ at its ends have been taken off, the fur or other deposit may be removed by drilling through the cylindrical 100 passages D⁴.

Cooling water is fed to the passages D⁴ in the arms by pipes G from a tank H carried at the top of the shaft A and is discharged through the pipes J. According 110 to the present invention, however, the feed pipes G do not extend continuously from the tank to the arm but are divided above or

about the top of the rabble shaft, at an accessible position. The upper portion G^1 of each feed pipe is fixed to the tank H and enters loosely the lower portion G . Preferably the lower portion G is provided with a cup- or funnel-like enlargement G^2 into which the upper portion G^1 dips, a tap or valve G^3 being provided on the upper portion to enable, when desired, the water to be cut off from that feed pipe. The diameter of the pipes G and J and passages D^4 being not less than that of the portion G^1 , this loose division of the feed pipe will not interfere with the circulation of the cooling water, but it provides simple and effective means for enabling any one arm D to be removed without disturbing any other part or the circulation of water through other arms. To perform this operation the valve G^3 of the arm concerned is closed, the lower portion G of the feed pipe is unscrewed from engagement with the inwardly projecting base D^1 of the arm, and either removed or displaced (the loose division enabling this to be done most easily), the discharge pipe J may then also be unscrewed and finally the arm D is dismounted by driving back the cotter E from a suitable aperture in the furnace wall. The removal of the cotter is very much facilitated by turning the arm D slightly in relation to the shaft in the same direction as that in which it normally moves, this slight movement of the arm generally loosening the cotter, since the construction is such that the resistance to the passage of the arm opposed by the ore being treated tends to lock the cotter and hence to increase the security of its connection to the shaft. The refractory filling at the two ends of the hole C preserves the cotter from the action of the heat and the chemical reactions, and prevents it from being fused or otherwise bound irremovably.

A further advantage obtained by the employment of the loose division of the feed pipe is that should the water passages D^4 in any arm become choked the consequent decrease of circulation will cause the water in the cup G^2 or its equivalent to overflow and thus to give a warning of the danger before the arm is burned or broken. Hence the arm indicated may be removed before it is damaged and its passages cleared after which it may be used again.

It will be seen that as the water pipes G and J do not occupy the whole of the hollow of the shaft, and as the base parts of the water-cooled arms do not block the channels of the shaft into which they extend, the shaft may itself be air cooled. In order to enable a forced draft to be used through the shaft, the water tank H is made annular as shown in Fig. 5 surrounding the shaft or an extension thereof and a removable casing K is provided surrounding the inner

wall of the tank, dipping below the water therein and leading to suitable means for sucking or forcing air through the hollow shaft as shown diagrammatically at L . The water is led from the tank to the arm by a removable bend G^4 passing through the shaft or its extension wall, the loose division of the feed pipe in this case being conveniently outside the shaft above the bend G^4 . All the water pipes inside the shaft are continued to the top of the shaft as shown in Fig. 5 so that they may be easily unscrewed from their arms when the casing K has been removed. The connection of the bend G^4 with the feed pipe G need not necessarily be water-tight; it may be of the same type as the loose division hereinbefore described, the bend entering through a suitable aperture in the feed pipe. It is preferred also to furnish a loose division outside the shaft for ease in removing the bend, but where such a loose connection between the bend and feed pipe is used it will be seen that in case of choking of the arm passages the overflow of water will take place inside the shaft and may be detected at the bottom thereof.

The improved means of securing arms to the shaft according to this invention also enable an air-cooled arm to be substituted for any one of the water-cooled arms, Fig. 4 illustrating an air-cooled arm adapted to be secured to the lug B as hereinbefore described, the end of the arm base being shaped to fit the longitudinal channel in the shaft so as to force the air to circulate through the arm in known manner.

What I claim and desire to secure by Letters Patent is:—

1. In an ore roasting furnace, the combination of a hollow shaft having an outwardly projecting hollow lug, provided with a transverse passage that intersects the bore of the lug, a rabble arm having a base approximately fitting the interior of the lug, and a locking pin arranged within the transverse passage in the lug and engaging the arm to secure it to the shaft, the pin being shorter than the passage whereby it is entirely within the lug when in operative position. 105

2. In an ore roasting furnace, the combination of a hollow shaft having an outwardly projecting hollow lug, provided with a transverse passage that intersects the bore of the lug, a rabble arm having a base approximately fitting the interior of the lug, a locking pin arranged within the transverse passage in the lug and engaging the arm to secure it to the shaft, the pin being shorter than the passage whereby it is entirely within the lug when in operative position, and a suitable refractory filling within the ends of said passage. 110

3. In an ore roasting furnace, the combination of a hollow shaft having an out- 125

wardly projecting hollow lug provided with a transverse passage that intersects the bore of the lug, a rabble arm having a base approximately fitting the interior of the lug, and a locking pin arranged within the transverse passage in the lug and engaging the arm to secure it to the shaft, the relative position and shape of the passage and form of the pin being such that the resistance to movement of the arm offered by ore being treated acts to increase the locking action of the pin on the arm.

4. In an ore roasting furnace, the combination of a hollow shaft, a hollow arm 15 detachably connected with the shaft, and means for circulating cooling fluid through the arm including a supply pipe connected at one end with the arm, and comprising a plurality of sections, the section connected 20 with the arm being adapted to be detached from the arm independent of any manipulation of any other section.

5. In an ore roasting furnace, the combination of a hollow shaft, a plurality of hollow arms supported by the shaft, an upwardly extending pipe connected with each arm and terminating above the upper end of the shaft, and means for supplying cooling fluid to each of said pipes and permitting any one thereof to be disconnected from the attached arm independent of any adjustment of the others or the fluid supplying means.

6. The combination of a hollow shaft for mechanical ore roasting furnaces, a rabble 35 arm removably secured thereto, a tank carried thereby, a sectional feed pipe extending from the tank to the arm the upper section being fixed to the tank and extending into an enlargement upon the upper end 40 of the lower section near the top of the shaft and a return pipe from the arm to the exterior of the shaft, substantially as set forth.

7. The combination of a hollow shaft for 45 mechanical ore roasting furnaces, a rabble arm secured thereto, an annular tank surrounding the shaft, a removable casing surrounding the inner wall of the tank and connected to means for causing an air current therethrough, feed and return pipes 50 extending from the arm within the shaft to the top thereof, a removable hollow bend connecting with the feed pipe and extending through the shaft, and a pipe secured 55 to the tank entering loosely the upper end of the removable bend substantially as set forth.

In testimony whereof I have signed my name to this specification in the presence of 60 two subscribing witnesses.

JOHN HARRIS.
